(No Model.)

A. A. BENNETT.
MACHINERY FOR PREPARING CLAY.

No. 425,729.

Patented Apr. 15, 1890.

UNITED STATES PATENT OFFICE.

ARTHUR A. BENNETT, OF JACKSON, MICHIGAN.

MACHINERY FOR PREPARING CLAY.

SPECIFICATION forming part of Letters Patent No. 425,729, dated April 15, 1890.

Application filed November 19, 1889. Serial No. 330,926. (No model.)

To all whom it may concern:

Be it known that I, AETHUR A. BENNETT, of Jackson, in the county of Jackson and State of Michigan, have invented a new and useful 5 Improvement in Machinery for Preparing Clay for Working in Clay-Machines, of which the following is a specification.

This invention applies to the means employed for removing the clay from the bottom 10 of the wet-pan, in which it is prepared for making into tile.

In the practical operation of these machines considerable labor is involved in the work of removing the wet clay from the bottom of the 15 pan. This has been done generally by a shovel operated by hand and requires a strong man for carrying on the work. Attempts have been made for removing the clay by mechanical appliances, but those heretofore attempted 20 have not been satisfactory.

In the annexed drawings, making part of this specification, Figure 1 is a plan view of the wet-pan, and Fig. 2 is a vertical transverse section of the same. Fig. 3 is a section 25 showing the detent for confining the shovel.

The same letters are employed in all the figures in the designation of identical parts.

A is the wet-pan, which is a revolving pan with a flat bottom and a vertical rim, which 30 is rotated by bevel-gear B, communicating to the pan, say, forty to fifty revolutions per minute.

C is a bar extending across the frame above the pan and carries two wheels D D, which 35 rotate with the revolution of the pan, working the clay into proper consistency for being worked in the press or other machine. The rotation of the pan employed by the centrifugal action creates a tendency for the plastic 40 clay to move toward the rim of the pan; but it is common to add scrapers to give outward and central direction to the clay.

E is a mold-board having a handle E'. This mold-board is made of iron or steel, preferably in two pieces united by rivets or bolts, forming, however, when united, a single piece. This mold-board is, say, two and one-half inches wide at the point, gradually increasing in width at the upper end, where it is 45 about five inches wide. It is twisted about a quarter-turn. Somewhat less of the motion of

the pan is slow, so that while the point lies flat near or upon the bottom the upper end stands vertical, the side being gradually turned up from a horizontal to a vertical position. 55

The mold-board is attached to a slotted beam F, secured to the frame in an inclined position, the upper end of the mold-board being received in the slot, up which it may be 60 raised to adjust the position of the point according to the depth of the bed of clay in the pan. A latch G is attached by a hinge-joint to the handle end of the mold-board in a position to be readily grasped by one holding the 65 handle, and the catch of the latch is made with a beveled face like that of a night-latch and is engaged in notches F', formed in the beam F along the side of the slot. These notches are also beveled upon their lower 70 faces, so that the mold-board may be pushed down readily without interruption by the latch, while the vertical face of the latch, encountering the vertical face of the notch, will prevent the mold-board from being forced up 75 by the pressure of the clay. By this means it is only necessary for the operator to force down the mold-board to the proper depth, when the latch will hold it down. When the mold-board is pulled entirely up out of the 80 pan, it may be held up by a hook or bolt. The point rests near the bottom of the wet-pan when in operation and its outer edge is placed close to the rim. The inner edge of the mold-board is turned gradually from a horizontal 85 to a vertical position, so as to form an inner side of a trough of which the rim of the wet-pan is the outer side. The inner side of the mold-board gradually approaches the vertical rim, so that as the clay is caught up from the 90 bottom by the point of the mold-board it will be made by the rotation of the pan to travel up the slope of the mold-board, and will at the same time be directed outwardly by the curve of the inner side of the mold-board 95 until, reaching the top of the rim of the wet-pan, the clay will be discharged over the edge of the rim, falling into a hopper or other receptacle. By this means the work of clearing is very greatly facilitated, and the expense of 100 operating the machine considerably reduced, as the mold-board may be readily operated

by a boy, while the shovel commonly used taxes the strength of a man.

What I claim as my invention, and desire to secure by Letters Patent, is—

- 5 1. The combination, with a revolving wet-pan, of an adjustable mold-board E, twisted so as to have a horizontal point, and gradually curved to form a vertical side, drawing constantly nearer to the side of the pan, a handle E' by which the slope of the mold-board may be regulated, and a beam which carries the upper end thereof, substantially as set forth.
- 10 2. In combination with a revolving wet-pan,

an adjustable mold-board E, a beam F, and a latch G, substantially as set forth. 15

3. In combination with the revolving wet-pan, an adjustable mold-board E, and a slotted beam F, constructed and arranged substantially as set forth.

In testimony whereof I have hereunto set 20 my hand in the presence of two attesting witnesses.

ARTHUR A. BENNETT.
